UNITED STATES PATENT OFFICE

ALFRED NEEF, OF AUDUBON, NEW JERSEY

PLATE-CLAMPING MECHANISM FOR PRINTING PRESSES

Application filed June 27, 1930. Serial No. 464,337.

The present invention relates to improvements in means for securing stereotype plates to the cylinder of a printing press, and the object of the invention is to provide a simple but durable means for effectively connecting the plates and cylinder so that relative movement between them, either axially of the cylinder or circumferentially thereof will be positively prevented.

10 The invention is particularly applicable for use with presses employed for printing newspapers, as by it a material reduction in the amount of margin or space required at the fold of a sheet may be secured.

15 An embodiment of the invention will be described in connection with the accompanying drawing, but it is to be understood that there can be considerable modification or change in details from the form illustrated without departing from the invention, and except where specifically referred to in the appended claims, the invention is not intended to be limited to the exact arrangement shown.

20 In the drawings several of the parts are shown more or less conventionally.

In the drawing:

Figure 1 is a partial transverse section of a printing press cylinder having a plate secured thereon by a clip embodying the present invention.

25 Figure 2 is a section substantially on the line 2—2 of Figure 1, on a slightly enlarged scale.

Figure 3 is a section substantially on the line 3—3 of Figure 1.

30 Figure 4 is a perspective view of a portion of a stereotype plate adapted for use with the invention.

Figure 5 is a detail perspective of a clip embodying the invention, detached.

35 Referring to the drawing, in the several figures of which like parts are designated by the same reference characters, 1 designates a printing press cylinder, which is shown as provided with a plurality of longitudinally 40 extending channels adapted to receive clips for securing stereotype plates 2 radially against the surface of the cylinder. Such channels may be of the usual form and are of 45 greater width or area at their inner ends than

50 at the face of the cylinder, so that the plate securing clips are held against movement radially of the cylinder but may be adjusted longitudinally of the channels as desired to cooperate with plates of different widths.

55 The improved clip comprises a body 3 adapted to be received in and extend through any of the aforesaid channels formed in the printing cylinder and having at its inner end flanges 4, which are received in marginal extensions of said grooves, so that the clip cannot be radially disengaged from the printing cylinder. As shown, the clip body is of substantially rectangular form in cross section and of substantially the same width as the channel on which it fits.

60 At the outer end of the body 3 the clip is provided with a member 5, of substantially triangular form in cross section having oppositely beveled faces, either of which is adapted to cooperate with the inclined or beveled edge 10 of a stereotype plate 11, in substantially the same manner as the clips or plate securing means commonly employed.

65 The member 5 is of greater length than the body 3 of the clip, so that portions thereof project beyond opposite ends of said body.

70 The member 5 and body 3 of the clip are united by portions 6, which project laterally from the junction of the member and the body and the outer face of each of which is substantially perpendicular to the top surface of the body 3 and parallel to the sides of the body. The laterally projecting web 6 extends throughout the length of the clip body 3 and is adapted to fit in a notch 12 formed in the beveled edge 10 of the stereotype plate.

75 As shown in the drawing, the depth of the notch 12 is less than the width of the beveled edge 10 of the plate, and the length thereof corresponds to the length of the projection 6. When the projection 6 on the clip is in position in such notch, the end walls being in contact will effectively prevent movement of the plate over the surface of the cylinder.

80 It will be seen that the improved clip acts, by reason of the contact of one of its inclined faces with the beveled edge of the plate, to bind a plate radially against the printing cylinder; and, by reason of the en-

gagement of the projection 6 with the notch 12, to also positively prevent movement of the plate circumferentially of the cylinder.

The height of the projection 6 being less than the thickness or width of the adjacent inclined face of the member 5, the plate will be held radially against the cylinder throughout the length of the member 5.

In practice, the several clips in a channel in the cylinder 1 will be held against movement longitudinally thereof by any suitable means in the ordinary, usual manner.

As will be evident from Figures 2 and 3, the improvements enable two plates 11 to be positioned in closer relation than has been possible with the securing means heretofore commonly employed. Two plates corresponding to the opposed pages of a folded sheet can be positioned so that the lower edges 20 of the beveled sides 10 thereof will abut beneath the bottom edge of the member 5 (as shown in Figure 3) and thereby the blank space or margin at the fold, or between such pages, can be reduced to a minimum.

It will be seen that the width of the unprinted margin or fold will depend upon the distance between the plate engaging faces or sides of the member 5 of the clip. Instead of making this member of the form of a substantially equal-lateral triangle, as shown, it may be made of isosceles shape in cross-section with the base or outer face of less width than the plate engaging faces.

By the invention, a clip is provided which will exert a maximum amount of radial pressure on the plates, and in addition by the projections 6 is positively interlocked with the plates, preventing movement thereof over the surface of the cylinder.

The notches 12 may be formed in the plates 40 11 either when such plates are initially cast or at any subsequent time.

For example, in casting such plates in a hand box, it is merely necessary to add a projecting part which will form the notch when the plate is cast. With another type of casting box, wherein the bevel on the plate is cast at the bottom and a saw is employed for providing the top bevel as the plate is turned in moving from the box, the revolving cylinder would be provided with projecting pieces which slide over a groove when it enters the part where the casting occurs. With this type of apparatus, two projections would be provided for each plate, one being inside of the box when the plate is being cast, while the other is outside when the plate is being removed, the outer projections turning into the casting box as the cast plate is removed therefrom.

It is believed that the manner of using and advantages of the invention will be readily understood from the foregoing description in connection with the drawing.

I claim:

1. The combination of a plate cylinder, a plate thereon, and a clip mounted on the cylinder and adapted to exert pressure radially on the plate to clamp it to the cylinder, said plate and clip being also connected by a member on one engaging a recess on the other, whereby the plate is held from movement over the surface of the cylinder.

2. The combination of a plate cylinder, a plate thereon having a beveled edge, and a clip mounted on the cylinder and having a beveled surface adapted to cooperate with the beveled edge of the plate to clamp the latter radially against the cylinder, said plate and clip having also an interengaging projection and recess whereby movement of the plate over the surface of the cylinder is prevented.

3. The combination of a plate cylinder, a plate thereon having a beveled edge, and a clip mounted on the cylinder and having a beveled surface adapted to cooperate with the beveled edge of the plate to clamp the latter radially against the cylinder, one of said beveled portions being provided with a recess and the other with a projection fitting said recess and preventing movement of the plate over the surface of the cylinder.

4. The combination of a plate cylinder, a plate thereon having a beveled edge provided with a recess, and a clip mounted on the cylinder and having a beveled surface contacting with the beveled edge of the plate, on both sides of the recess therein, and a projection fitting in said recess, whereby the plate is clamped against the cylinder and positively held from movement over the surface of the cylinder.

5. The combination of a plate cylinder, a plate thereon having a beveled edge which is provided with a notch of less depth than the beveled surface, and a clip mounted on the cylinder and having a portion fitting in said notch and a beveled surface that contacts with the beveled surface of the edge of the plate throughout the length of and at opposite sides of the notch, for the purpose described.

6. The combination of a plate cylinder, a plate thereon having a notch formed in an edge which has a beveled surface at an end of the notch, and a clip mounted on the cylinder and having a portion fitted in said notch and a beveled surface extending from said portion over the beveled surface of the edge of the plate adjacent the notch therein, for the purpose described.

7. The combination of a plate cylinder, a plate thereon, and a clip mounted on and projecting radially from the cylinder and provided at its outer end with a member extending circumferentially of the cylinder and having a beveled face, adapted to cooperate with an edge of the plate to clamp the plate against the cylinder, and an ele-

ment of means, comprising a projection and cooperating recess, for interlocking the clip and plate to prevent movement of the latter over the surface of the cylinder.

- 5 8. The combination of a plate cylinder, a plate thereon, and a clip mounted on and projecting radially from the cylinder and provided at its outer end with a member extending circumferentially of the cylinder 75 and having a beveled face, adapted to cooperate with an edge of the plate to clamp the plate against the cylinder, and a shoulder of less length and width than said beveled face, adapted to engage a recess in the 10 plate to prevent movement of the latter over the surface of the cylinder.

- 15 9. The combination of a plate cylinder, a plate thereon, and a clip mounted on and projecting radially from the cylinder and 20 provided at its outer end with a member extending circumferentially of the cylinder and having a beveled face, adapted to cooperate with an edge of the plate to clamp the plate against the cylinder, and an element of 25 means, comprising a projection and cooperating recess, for interlocking the clip and plate to prevent movement of the latter over the surface of the cylinder, the beveled surface member projecting beyond opposite 30 sides of the clip body and having the lower edges of its projecting end portions radially spaced from the cylinder a distance in excess of that separating the cylinder and the means for interlocking the clip and plate.

- 35 10. A clip to hold printing plates in position on a plate cylinder comprising a body, adapted to be secured at its base to a cylinder, having a beveled surface adapted to contact with a beveled edge of a printing plate 40 to clamp such plate radially against the cylinder, and with a projection adapted to engage a recess in the plate to prevent movement of the latter over the surface of the cylinder.

- 45 11. A clip to hold printing plates in position on a plate cylinder comprising a body, adapted to be secured at its base to a cylinder, having at its upper end a beveled face adapted to engage the beveled edge of a 50 printing plate and clamp the plate radially against a cylinder and provided adjacent said beveled face with a shoulder adapted to engage a cooperating part on the plate to prevent movement of the plate over the surface of the cylinder.

- 55 12. A clip to hold printing plates in position on a plate cylinder comprising a body, adapted to be secured at its base to a cylinder, having at its upper end a member which 60 has oppositely inclined faces diverging outward from its lower edge to provide beveled surfaces adapted to engage beveled edges of printing plates, between which the clip is positioned, to clamp said plates radially 65 against a cylinder, said clip body being pro-

vided adjacent each of the beveled surfaces thereon with one element of means, comprising a projection and cooperating recess, for positively interlocking the clip and plate to prevent movement of the latter over the surface of the cylinder.

13. A clip to hold printing plates in position on a plate cylinder comprising a body, adapted to be secured at its base to a cylinder, having at its upper end a member which has 75 oppositely inclined faces diverging outward from its lower edge to provide beveled surfaces adapted to engage beveled edges of printing plates, between which the clip is positioned, to clamp said plates radially 80 against a cylinder, said clip body being provided adjacent each of the beveled surfaces thereon with one element of means, comprising a projection and cooperating recess, for positively interlocking the clip and plate to prevent movement of the latter over the surface of the cylinder, the beveled surfaces of the clip being of such length that they project beyond opposite sides of the clip body.

In testimony whereof I have hereunto set my hand.

ALFRED NEEF.
